(57) **CLAIM**

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken lines immediately adjacent to the shaded area define the bounds of the claimed design, and form no part thereof. The seven unshaded areas within the shaded area that are demarcated by broken lines form no part of the claimed design. The broken line showing of eyelets and the remainder of the shoe are for environmental purposes only and form no part of the claimed design.
